UNITED STATES PATENT OFFICE.

CARROLL KNOWLES, OF HARTFORD, CONNECTICUT, ASSIGNOR TO PRATT & WHITNEY COMPANY, OF NEW YORK, N. Y., A CORPORATION OF NEW JERSEY.

CLAMPING MECHANISM FOR PLANER RAILS.

Application filed August 13, 1920. Serial No. 403,380.

To all whom it may be concern:

Be it known that I, CARROLL KNOWLES, a citizen of the United States, residing at Hartford, in the county of Hartford and 5 State of Connecticut, have invented certain new and useful Improvements in Clamping Mechanisms for Planer Rails, of which the following is a specification.

This invention relates to planers and particularly to a mechanism for clamping the cutter-supporting cross rail to the uprights thereof, and it is the general object of the invention to provide an improved mechanism for performing this function.

10 In machines of the type illustrated herein the cutter-supporting rail is vertically adjustable on the uprights and clamping devices are mounted on the rail in position to engage the uprights to clamp the rail there- 20 to in its adjusted position. It has been heretofore proposed to provide two clamping members, one for each upright, and a single means having a bearing action against the 25 clamping members to perform the clamping operation. In such a construction the two 30 clamping members must be exactly alike and must be adjusted to exactly correspond with each other. They must fit the rail and the two uprights with an equal precision if 35 the clamping action on the two uprights is to be the same. However, since such accuracy cannot be maintained, the major portion or all of the clamping action may take 40 place on one upright. Such upright must therefore withstand the thrust of the tool 45 while the clamp at the other end of the rail may be loose and therefore perform little or no holding or clamping action. It is accordingly an object of the present invention to provide a clamp-operating means 50 wherein the clamping effect on the two uprights is equal. This object may be accomplished in a variety of ways of which the one illustrated herein is an example.

45 Referring to the figures of the drawing:

Figure 1 is a front elevation of a planer comprising the present invention.

50 Fig. 2 is an enlarged horizontal trans- 55 verse section through the planer on the line 2-2 of Fig. 1 and illustrating the improved cutter-supporting cross rail clamping means.

Fig. 3 is a detail view of the right end of the cross rail and illustrates the clamp-oper- 60 ating handle.

55 Referring more specifically to the draw-

ing by reference characters, 1 indicates the base, 2 the reciprocating table thereon, and 3 the uprights mounted on the base at opposite sides of the table. 4 indicates the cutter-supporting rail mounted on the uprights 60 3 and adapted to be vertically adjusted thereon by means of screws 5 threadedly engaging nuts or lugs 5^a on the rail. A side head cutter support 6 is mounted on one upright 3 and may be adjusted vertically thereon by means of a screw 7. Cutter heads 8 mounted on the rail 4 may be adjusted horizontally therealong by means of screws 9 and 10. The cutter feeding mechanism which within itself forms no part of this 70 invention is shown generally at 13 and 14 and comprises the usual rack and pinion and ratchet mechanisms to the feed screws 9 and 10 and screw 7. The cutters are adapted to the adjusted toward and from the 75 work by means of hand wheels 6^a and 8^a. Belts 11 and 12 operating on belt pulleys 11^a and 12^a respectively are provided for reciprocating the table 2.

The clamping mechanism comprising the 80 present invention is shown more clearly in Fig. 2 wherein clamping means, as the two levers 15, is mounted on the rail, one lever being pivoted adjacent each upright. Each 85 clamping lever comprises a long arm 15^a and a short arm 15^b, each lever being secured at its fulcrum to the rail by means of a tap bolt 16 passing loosely through the lever and threadedly engaging the rail. A pair 90 of washers 17 having curved engaging surfaces are mounted on each bolt between the bolt head and the lever, such construction of the washers providing for a rocking movement of the levers. The short arm 15^b of each lever is adapted in the clamping 95 action to engage the surface 18 at the rear of its respective upright.

In accordance with the invention I pro- 100 vide a single means for engaging and operating the clamping levers and I mount a differential or equalizing member between this means and the clamping levers whereby an equal clamping pressure will be imparted from the levers to the uprights. The operating means illustrated herein comprises a 105 cam 19 preferably formed as an eccentric on a shaft 20 parallel with the rail 4 and adapted to be operated by a handle 21. To avoid friction a roller 19^a is preferably mounted on the cam 19. The equalizing 110

member comprises a plate 22 having pins 23 threaded therein and loosely engaging in bores 24 in the free ends of the long arms 15^a. As illustrated, the plate is adapted to 5 be engaged directly by the roller 19^a.

In Fig. 2 and in the full lines of Fig. 3, the rail is shown as clamped to the uprights. When it is desired to adjust the rail vertically the handle 21 is moved to the position 10 illustrated in dot-and-dash lines in Fig. 3, which movement releases the pressure of the roller 19^a on the arms 15^a and likewise releases the pressure of the arms 15^b on the uprights 3, thus leaving the rail free to slide 15 vertically on the uprights. To clamp the rail in its adjusted position the handle 21 is moved to the full-line position illustrated in Fig. 3. This action of the shaft 20 through 20 the cam 19 thereof forces the roller 19^a 25 against the plate 22 which, being loosely mounted in the ends of the arms 15^a, exerts equal pressure against such arms and likewise exerts an equal clamping pressure of the arms 15^b against the uprights 3. As 30 will be noted, the use of the equalizing plate 22 assures an equal clamping pressure at both ends of the rail even though the levers 15 are unequally adjusted on the rail and regardless of any foreign matter which may 35 get between the clamping surfaces 18 of the uprights and the arms 15^b.

What I claim is:

1. In a machine tool, the combination of 35 two supports, a member mounted for sliding movement on such supports, a clamping means pivoted on the member adjacent each support, and cam operated means including a differential connection between and in operative connection with the two clamping 40 means for operating the same with equal pressure against the two supports.

2. In a machine tool, the combination of 45 two supports, a tool-supporting member mounted for sliding movement on such supports, a clamping member mounted on the tool-supporting member adjacent each support, means for forcing the clamping members into clamping engagement with the two supports, and an equalizing member between 50 the said means and the clamping members whereby the clamping members are operated with an equal pressure against the two supports.

3. In a machine tool, the combination of 55 two uprights, a cutter-supporting rail mounted for vertical sliding movement on the uprights, a clamping lever mounted on the rail adjacent each upright, a cam on the rail for forcing the clamping levers into 60 clamping engagement with the uprights, and

an equalizing member between the cam and clamping levers whereby the levers are operated with an equal pressure against the two uprights.

4. In a machine tool, the combination of 65 two uprights, a cutter-supporting rail mounted for vertical sliding movement on the uprights, a clamping lever pivoted to the rail adjacent each upright, each lever comprising a long and a short arm, the short 70 arm of each lever being adapted to clamping engage its upright, a cam on the rail for operating the levers to clamp the rail to the uprights, and an equalizing member loosely connected to the long arms of the 75 levers and adapted to be operated on by the cam whereby in the clamping operation the pressure exerted by the cam is divided equally between the two levers.

5. In a machine tool, the combination of 80 two uprights, a cutter-supporting rail mounted for vertical sliding movement on the uprights, a clamping member mounted on the rail adjacent each upright, a rotary cam on the rail for operating the clamping 85 members, and an equalizing member between the cam and the said clamping members whereby the clamping action of the cam is distributed equally to the clamping members against their respective uprights.

6. A rail clamping device for machines of the character described, comprising a rail, a pair of supports therefor, a pair of clamps pivotally secured to said rail, and having clamping surfaces for engaging said supports and means for operating said clamps comprising an equalizer element, operatively 95 connected to the same.

7. A rail clamping device for machines of the character described, comprising a rail, a 100 pair of supports therefor, a pair of clamps pivotally secured to said rail, and having clamping surfaces for engaging said supports and means for operating the same comprising a member free to move automatically 105 to compensate for unequal pressure exerted against the clamps.

8. A rail clamping device for machines of the character described, comprising a rail, a pair of supports therefor, a pair of clamps 110 pivotally fastened to the said rail and having clamping surfaces adapted to engage the said supports, a rotary shaft extending longitudinally of the said rail, and means operable by the rotation of the said shaft and 115 adapted to actuate the said clamps.

In testimony whereof, I hereto affix my signature.

CARROLL KNOWLES.
